United States Patent Office

Des. 203,496
Patented Jan. 18, 1966

203,496

VEHICLE

Edward D. Bell, Los Angeles County, Calif.
(5830 Denny Ave., North Hollywood, Calif.)

Filed May 11, 1965, Ser. No. 85,226

Term of patent 14 years

(Cl. D14—3)

The dominant features of the design reside in the portions shown in full lines.

I claim:

The ornamental design for a vehicle, substantially as shown and described.
